(57) **CLAIM**

The ornamental design for a roof lining for golf carts as shown and described.

DESCRIPTION

FIG. 1.1 is a front perspective view of a roof lining for golf carts showing our new design;

FIG. 1.2 a rear perspective view thereof;

FIG. 1.3 is a front elevational view thereof;

FIG. 1.4 is a rear elevational view thereof;

FIG. 1.5 is a left side elevational view thereof;

FIG. 1.6 is a right side elevational view thereof;

FIG. 1.7 is a top plan view thereof; and

FIG. 1.8 is a bottom plan view thereof.
